ATTORNEYS'

UNITED STATES PATENT OFFICE.

JOSEPH F. STABELL, OF BUFFALO, NEW YORK.

APPARATUS FOR USE IN ROAD-BED CONSTRUCTION.

1,349,012.

Specification of Letters Patent. Patented Aug. 10, 1920.

Application filed March 1, 1920. Serial No. 362,518.

To all whom it may concern:

Be it known that I, JOSEPH F. STABELL, a citizen of the United States, residing at Buffalo, in the county of Erie and State of New York, have invented a new and useful Improvement in Apparatus for Use in Road-Bed Construction, of which the following is a specification.

This invention relates more particularly to portable apparatus adapted for use in road construction work.

One object of the invention is to provide a turntable adapted to be associated with a concrete mixer or other road material handling machine, so that a truck or vehicle loaded with the material for the mixer or other machine can be driven forwardly onto the turntable and turned about by rotating the turntable so that the material can be dumped directly from the rear of the vehicle into the mixer or other machine, thereby making it unnecessary to carry the material in small quantities from a distance to the mixer, and thus saving a great deal of labor otherwise required in handling the material.

Another object is to mount the turntable on a wheeled carriage adapted to be supported by and to travel on the temporary parallel curbs or forms which are ordinarily used at opposite sides of the road for confining the concrete or other road material, and to construct the carriage with a drop or underslung frame disposed between the temporary curbs so that the top surface of the turntable is not objectionably high; and to construct the turntable and its carriage so that both will be entirely out of contact with the road bed.

Another object is to construct and arrange the turntable so that it may be moved with the concrete mixer or other machine as the latter is advanced step by step ahead of the work.

Another object is to improve portable apparatus of this sort in other respects hereinafter described and set forth in the claim.

In the accompanying drawings:

Figure 1 is a side elevation, partly in section, of a portable turntable embodying the invention, showing the same associated with a concrete mixing machine and detachably connected thereto.

Fig. 2 is a longitudinal sectional elevation

of the turntable and its supporting carriage, on line 2—2, Fig. 3, on an enlarged scale.

Fig. 3 is a top plan view thereof, showing the carriage in position on the curbs.

Fig. 4 is a front elevation thereof.

In the construction of concrete or similar roads, the present practice is to prepare a roadbed or foundation of coarse, broken stone or the like, which is rolled to form a suitable surface for the reception of the concrete. Temporary metal or other curbs or forms are arranged parallel to each other at opposite sides of the road bed to confine the concrete until it is set and the forms are then removed. The concrete is preferably discharged from the concrete mixer, which is moved along the road bed in advance of the work. It is not practical, however, to drive the heavy loads of cement and sand or other material for the mixer directly to the mixer, as the space between the curbs is limited and turning the vehicle around would disturb the surface of the road bed. The material has, therefore, heretofore usually been discharged at some distance from the mixer and then taken to the mixer in wheelbarrows or otherwise, which results in a considerable expense for time and labor.

The present invention is intended to eliminate this expense and labor by arranging the turntable on a carriage adapted to travel along the curbing in such relation to the mixer that a truck or vehicle can be driven over a relatively short, movable inclined approach up onto the turntable, and by rotating the turntable the rear end of the vehicle placed in position to dump or discharge the material directly into the receiving hopper of the mixer.

The inclined approach, the turntable carriage and the concrete mixer are preferably detachably connected together and may all be simultaneously moved along as the work progresses.

In Fig. 1 of the drawings the roadbed is shown at 10 and parallel metal curbs 11 are arranged, as usual, at opposite sides thereof and project above the surface of the roadbed. The concrete is spread between these curbs as it is discharged from the chute *a* of a concrete mixer A. These curbs may be of any usual or suitable sort but are preferably of the form shown in the drawings, each curb consisting of a metal rail

having a vertical wall 12 arranged on the inner side or toward the concrete filling and forming a retaining wall therefor, a base flange 13 adapted to support the curb, and 5 an outwardly-bent, top flange 14 forming a track or guide for the supporting wheels of the turntable carriage.

The mixer shown has a receiving hopper *a'* adapted to be lowered to a position on or 10 adjacent the road bed to receive the material discharged from the rear end of a truck or other vehicle *B*, and to be raised for discharging the material into the mixing drum. The mixing machine *A* is mounted on wheels 15 to adapt it to be moved along as the work progresses. The turntable *C* may be of any suitable construction adapted to revolve on its supporting carriage *D*. The turntable *C* shown in the drawings comprises a central 20 circular bearing plate 20, rotatable on upper and lower ball bearings in races 21, 22 provided on a circular base 23, rigidly secured on an underframe 24 of the carriage *D*, and a platform 25 secured on the plate 20, and comprising a frame composed of I beams 26 or the like, surrounded by a circular peripheral channel beam 27, and covered with planks 28 or the like to form the supporting surface for vehicle *B*. Any other 30 suitable construction for the turntable may be used.

The supporting carriage *D* for the turntable *C* is preferably constructed as follows:

The underframe 24 before mentioned, 35 preferably comprises spaced longitudinal beams 35 connected between their ends by transverse bars 36, forming a four-sided support for a horizontal plate or the like on which the turntable base 23 is secured. The 40 outer ends of the bars 35 are rigidly secured to parallel transverse I beams 38 disposed on opposite sides of the axis of the turntable *C* and their length is substantially equal to the width of the road between the curbs 11, 45 (see Fig. 3.) The opposite ends of these beams 38 are suitably secured, as by means of depending hangers or brackets 39, to carriage side frames 40, 41, respectively, each of which preferably comprises longitudinal, 50 spaced, channel beams 42 extending parallel with and at opposite sides of the top 14 of the curbs 11, and connected between their ends by spacing members 43. The hangers 39 are conveniently secured between the spacing members 43 and the vertical face of 55 one of the beams 42.

Means are preferably provided for bearing on the tops 14 of the curbs 11 for supporting the carriage thereon and permitting it to be 60 readily moved along on these curbs as the work progresses. The means shown in the drawings comprise flanged rollers 45 journaled between the beams 42, preferably at or near their outer ends on shafts 46. Additional rollers may be provided if necessary,

or any other suitable means for movably supporting the carriages *D* on the curbs 11 could be used.

The carriage constructed as described with the underslung or drop frame extending low 70 down between the curbs, enables the top surface of the turntable *C* to be located at a convenient height for driving the vehicles thereon, and a strong, rigid construction is provided, and one which allows the turntable to be readily rotated and moved along the curbs.

An inclined approach 50 of any desired construction is provided whereby a truck or vehicle may be driven from the road bed up 80 onto the turntable. This approach is portable and is readily moved with the turntable, and is preferably detachably secured thereto as by hooked bars 51 bolted to the longitudinal frame bars of the approach and projecting therefrom and adapted to be hooked on the carriage under the frame, as shown in Fig. 2.

If desired, the turntable carriage *D* may be detachably secured to the mixing machine *A* so that these units as well as the inclined approach 50 may all be simultaneously advanced as the work progresses. For this purpose, adjustable connecting rods 55 are shown which are attached at one end to 95 a part on the front end of the mixing machine and at the other ends are suitably secured to the rear cross beam 38 of the carriage. Any other suitable means may be used for this purpose.

By the described construction the supporting wheels for the turntable are located at the sides of the turntable beyond the periphery thereof and are adapted to travel on the usual raised curbs or tracks at the opposite sides of the road bed; while the turntable carriage depends between the tracks close to the road bed so that the turntable can be located low down with the top only a short distance above the roadbed, thus adapting trucks to be readily driven up onto and stopped on the turntable. Nevertheless, the turntable and its carriage are wholly supported off of the roadbed so as not to disturb the same. The turntable, its inclined approach and the mixing machine are connected so that they can be moved or advanced as a unit as the work progresses, but they can be readily disconnected to facilitate the separate manipulation and transportation of the several devices.

I claim as my invention:

In a road construction apparatus, the combination of a turntable, a carriage on which said turntable is rotatably mounted, wheels 125 journaled on said carriage at its opposite sides, and adapted to roll on raised tracks at opposite sides of the road bed between which tracks said carriage depends, an inclined approach detachably connected to one end of 130

said carriage, and a machine detachably connected to the opposite end of said turntable carriage, whereby a vehicle can be driven up onto said turntable and turned to a position to discharge material therefrom into said machine, and said turntable, said approach and said machine can be simultaneously advanced as the work progresses.

Witness my hand this 24th day of February, 1920.

JOSEPH F. STABELL.
